United States Patent Office

Des. 204,755
Patented May 17, 1966

204,755

DAVENPORT OR SIMILAR ARTICLE

Jack Wilson, 5556 Centinela Blvd., Los Angeles, Calif.

Filed June 23, 1964, Ser. No. 80,528

Term of patent 14 years

(Cl. D15—11)

FIG. 1.

FIG. 2.

FIG. 3.

FIG. 4.

FIG. 5.

FIG. 2 is a right end view of FIG. 1 taken substantially on line 2—2 of FIG. 1.

FIG. 3 is a section taken substantially on line 3—3 of FIG. 1.

FIG. 4 is a rear view of the davenport; and

FIG. 5 is a section taken on line 5—5 of FIG. 3.

The end of the davenport not shown is the same in appearance as the end shown.

I claim:

The ornamental design for a davenport or similar article, substantially as shown and described.
